Primary Examiner — Brandon M Rosati*Assistant Examiner* — Marissa J Cash(57) **CLAIM**

The ornamental design for a combination balloon mold and uninflated balloon.

DESCRIPTION

FIG. 1 is a side elevational view of the balloon mold. The other side is identical.

FIG. 2 is a top plan view of the balloon mold.

FIG. 3 is a bottom plan view of the balloon mold.

FIG. 4 is a side perspective view of the balloon mold.

FIG. 5 is a side view of the uninflated balloon using the balloon mold.

FIG. 6 is a front view of the uninflated balloon using the balloon mold.

FIG. 7 is a front view of the combination balloon mold and uninflated balloon; and,

FIG. 8 is a side view of the combination balloon mold and uninflated balloon.

1 Claim, 2 Drawing Sheets(56)
